CONTAINER FOR TUBES AND BULBS

William A. Ringler, Wayne, Pa.

Application July 21, 1934, Serial No. 736,289

27 Claims. (Cl. 229—39)

This invention relates to a container for tubes and bulbs and more particularly to a container for radio tubes, electric light bulbs and similar products which are generally examined and tested after packaging and before being passed on to the consumer or user.

5 Delicate instruments, such as radio tubes, electric light bulbs and similar products, often become damaged through shock so as to be no longer operative. The purchaser or consumer of such products generally requires a test to be made immediately before purchase to determine that the merchandise is in good workable condition. Containers for such products have heretofore been constructed to facilitate opening of the container and removal of the contents at all times for purposes of test.

10 The bootlegging of inferior products in containers bearing the trademark of the manufacturer of a high grade product has become prevalent, particularly in the radio tube and electric bulb industry. The removal of a recognized high grade product from its container and the insertion therein of an inferior or ineffective product has been made easy by reason of the fact that the product must be made accessible at all times for test. No container has heretofore been designed which would permit the performance of proper tests of the contents at all times and at 15 the same time prevent unauthorized removal and separation of the contents from the container.

20 Furthermore, containers heretofore provided have not properly protected the delicate contents and large losses from breakage and damage have resulted. The method heretofore used for packaging the product has also been cumbersome and expensive and has been largely performed by hand.

25 An object of this invention is to provide a container especially adapted for the packaging of radio tubes and electric light bulbs, which will permit proper test and examination of the contents, but prevent unauthorized removal thereof.

30 Another object of this invention is to provide a container for delicate tubes and bulbs having means which will permit quick ejection of the contents for test and at the same time will leave telltale evidence if the contents are improperly tampered with and will require irreparable destruction of the container if the original contents are to be removed.

35 Another object of this invention is to provide a container for tubes, bulbs and the like which fully protects the contents from shock and injury and yet renders the contents readily accessible for test at all times.

40 Still another object of this invention is to provide a method for packaging radio tubes and bulbs quickly and economically with a minimum of hand operation.

45 Still another object of this invention is to provide a container which may be manufactured, packed and assembled in an economical manner substantially entirely by automatic machinery, which requires a minimum of material, which is strong, durable and foolproof in construction, which fully protects the contents against injury, which is easy to operate, and which can be made into a variety of attractive designs and patterns.

50 Other objects of this invention will become apparent as the disclosure proceeds.

55 The container forming the subject matter of this invention comprises generally an outer tubular member having enclosing side walls within which the radio tube or electric bulb is contained. The article itself may be wrapped with suitable advertising and contained within a corrugated paperboard shell. An inner member is then wrapped around the article lengthwise thereof and the inner member and assembled 20 contents inserted into the outer tubular member. The inner member comprises one or more partitions which telescope within and extend transversely across the outer container. One of the partitions is provided with a center opening 25 through which the test end of the article extends. The test end of the tube or bulb is ejected beyond the end of the outer member by a telescoping movement of the inner member within the outer member. Guide flaps, extending 30 from the partitions, facilitate the telescoping movement. The telescoping movement of the inner member, however, is definitely limited and the inner member cannot be removed from the outer member without leaving telltale marks of 35 tampering or requiring irreparable destruction of the container. This is accomplished by the provision of a flap which extends from one of the partitions and is creased transversely to provide accordion folds therein. The free end of 40 the flap is permanently secured to the outer container by means of an eyelet, staple or rivet which is so made that it cannot be removed without destroying or lacerating surrounding 45 parts of the container leaving telltale marks of tampering. The accordion folds in the flap permit free telescoping movement of the inner member within definite limits sufficient to permit the test end of the tube to be inserted into a 50 suitable electric socket.

55 The packing of the radio tube or electric bulb within the inner member may be performed automatically by a simple wrapping operation on a folding and gluing machine. The inner container may also be assembled by interlocking 55 the parts together either by hand or automatically. The inner container with the merchandise packed therein is then telescoped into the outer container and the packaging is completed 60 by the application of one or more rivets to secure

the accordian flap associated with the inner member to the outer member.

In order that a clearer understanding of my invention may be had, attention is hereby directed to the accompanying drawings, forming a part of this application and illustrating certain possible embodiments of my invention.

Referring to the drawings:

Fig. 1 is a perspective view of the completed container showing a radio tube inserted therein;

Fig. 2 is a perspective view of the inner member as it appears when fully packed with the radio tube therein;

Fig. 3 is a perspective view of the outer tubular member fully assembled and ready to receive the inner member and its contents;

Fig. 4 is a vertical cross-sectional view through the fully packed container showing a radio tube positioned therein, this view being taken on line 4-4 of Fig. 1;

Fig. 5 is a vertical cross-sectional view through the completed container showing the radio tube therein partially ejected into test position;

Fig. 6 shows a blank from which the inner member is formed;

Fig. 7 is a perspective view of the inner member in partially assembled form;

Fig. 8 is a perspective view of the inner member fully assembled with a radio tube packed therein, certain parts being broken away to more clearly illustrate the construction;

Fig. 9 is an enlarged vertical cross-sectional view through the packed container showing particularly the means used for permanently securing the inner member to the outer member;

Fig. 10 is a perspective view through the packed container, parts being broken away to illustrate certain features of the construction;

Fig. 11 is a perspective view of an inner member about to be applied to a radio tube and the surrounding shell and wrapping, the inner member here shown being of somewhat modified construction;

Fig. 12 is a perspective view of the completed inner member and tube as shown in Fig. 11;

Fig. 13 shows a blank from which an inner member of further modified form may be made;

Fig. 14 is a perspective view of the inner member formed from the blank shown in Fig. 13 and partially assembled;

Fig. 15 is a perspective view of the inner member shown in Fig. 14 as it appears when fully assembled;

Fig. 16 is a vertical cross-sectional view through a fully packed container having the inner member shown in Fig. 15 telescoped within a tubular outer member such as shown in Fig. 3;

Fig. 17 is a vertical cross-sectional view through the packed container shown in Fig. 16, the tube being shown partially ejected in position for test; and

Fig. 18 is a horizontal cross-sectional view through the container and its contents shown in Figs. 16 and 17, this view being taken on line 18-18 of Fig. 16.

Similar reference characters refer to similar parts throughout the several views of the drawings and specification.

Referring more particularly to Figs. 1 to 5, inclusive, the container comprises generally an outer member A of tubular form within which is telescoped an inner member B containing the tube or bulb. The outer member A may be

either polygonal or circular in cross-section. The outer member, shown in Fig. 3 for the purpose of illustration, is of rectangular form and comprises side wall portions 1, 2, 3 and 4 retained in tubular form by means of a flap 5 glued to the side wall portion 1.

The inner member B may be formed from a single blank of paperboard material such as shown in Figs. 6 and 7. The blank comprises side wall portions 10 and 11 hinged to the end wall portion 12 along score lines 13. Guide flaps 21, hinged to the end wall portion 12 along the score lines 22, extend laterally therefrom.

An end wall portion 14 is hinged to the side wall portion 10 along the score line 15 and is provided with a side wall flap 18 hinged to the end wall portion 14 along the score line 15. The side wall flap 18 is adapted to overlap the connecting flap 16, hinged to the side wall portion 11 along the score line 17 when the inner member B is assembled. As shown more particularly in Fig. 8 the side wall flap 18 may be further provided with an interlocking flap 19 hinged thereto along the score line 20. The interlocking flap 19 may be tucked under or behind the downturned flap 16 in the manner shown in Fig. 8 so as to connect the side wall portion 11 to the end wall portion 14.

In packaging, the tube or bulb T is preferably inserted into a tubular corrugated shell C designed to protect the sides of the tube against destruction or injury from shock. The contact end of the article T, comprising for example the prongs p in the case of a radio tube, is then inserted through an opening 29 in the end wall portion 12, as shown more particularly in Fig. 9. The side wall portions 11 and 12 and the end wall portion 14 are wrapped around the article T longitudinally thereof and the interlocking flap 19 is folded in back of the downturned flap 16, thus enclosing the article T and the protective shell C within the inner member B. The interlocking of flap portions 18 and 19 with the flap 16 may be performed either by hand or automatically by machine. The end wall portion 14 may also be provided with a suitable opening 30 therein through which the end portion t of the tube T may project. The opening 30 also serves to center the tube or bulb within the inner member.

The inner member B enclosing the article T is then telescoped into the outer tubular member A. The guide flaps 21 extending from the end portion 12 are bent to slide along the inside surface of the tube A. The end wall portion 14 is provided with one or more accordian flaps extending laterally therefrom as shown in Figs. 6, 7, 9 and 10. The accordian flap is formed by the flap portions 25, 26 and 31 hinged together along score lines 28 and 32 respectively and to the end wall portion 14 along the score line 27. Where only one accordian flap, extending laterally from one side of the end wall portion, is used, a guide flap 23 may be hinged along the score line 24 to the other side of the end wall portion 14.

The flap portions 25, 26 and 31 are folded over each other in accordian form in the manner shown in Figs. 9 and 10. A rivet or eyelet 50 is then inserted through the side wall 1 of the outer member A and the flap portion 31 of the accordian fold, permanently securing the parts together. The rivet or eyelet 50 is so constructed that when attached it cannot be removed without telltale disfiguration or irreparable destruc-

tion of the container. The end wall portions 12 and 14 extend transversely across the ends of the outer member A providing partition walls which completely close the ends thereof. The end wall portions 12 and 14 are normally positioned some distance within the ends of the outer member A so as to fully protect the projecting contact parts *p* and tip *t* from injury. When the tube or bulb is to be tested, slight downward pressure exerted on the partition 14 will telescope the inner member B and the bulb or tube contained therein so as to eject the contact parts *p* beyond the outer end of the member A. The contact parts *p* may then be freely inserted into a suitable socket or other apparatus so as to test the tube or bulb. When the guide flaps 21 pass the extreme end of the outer member A, the flaps will flare outwardly giving unobstructed access to the socket. When the contact parts *p* are to be moved into position for test the accordion flap unfolds as shown in Fig. 5, permitting the required telescoping movement of the inner member B. The inner member, however, cannot be removed from the outer member A without tearing off the accordion flap or doing visible damage to the container because the accordion flap is permanently secured to the outer member by the rivet or eyelet 50.

A somewhat modified form of inner member B is illustrated in Figs. 11 and 12. In this form the side wall flap 18 is somewhat extended, and the side flap 11 is somewhat curtailed in length. The side wall portion 11 and the engaging flap 18 may be coated with glue and either secured 35 directly to the outer surface of the protecting shell C or secured together in overlapping relationship. The side wall portion 10 may also be coated with glue if desired to prevent movement of the article T and its containing shell C with- 40 in the inner member B. The inner member B, shown in Figs. 11 and 12, may be wrapped around the article T and its protecting shell C automatically on a gluing and folding machine.

There is shown in Figs. 13 to 18, inclusive, a 45 container having an inner member B further modified in construction. As shown more particularly in Figs. 14 and 15, the side wall portion 11 of this inner member is provided with a hook portion 46 adapted to interlock with a hook 50 portion 45 extending from the flap portion 18. This inner member encircles the tube or bulb longitudinally as before, and is retained in assembled position by interlocking the hook portions 45 and 46. This operation may be per- 55 formed by a simple hand operation or automatically by machine.

The tube or bulb may be substantially completely enclosed within the inner member by side flaps 41 hinged to the side wall portion 10 along 60 the score lines 42 and by the side flaps 43 hinged to the side wall portion 11 and flap portion 18 along the score lines 44. When completely assembled the inner member B appears as shown in Fig. 15. The inner member may also be pro- 65 vided with two accordion folds attached by an eyelet or rivet 50 to the opposite side walls of the outer member A. The inner member shown in Figs. 15 to 18, inclusive, operates in the same manner as the inner members shown in Figs. 6 70 to 12, inclusive.

It is now seen that a container has been provided which is especially adapted for the packaging and merchandising of radio tubes and electric light bulbs which will permit testing 75 and examination and prevent unauthorized re-

moval from the container. The container is made of few parts which can be assembled substantially or entirely by automatic machinery with a minimum of material and a minimum of waste. The entire package may be assembled and packed in three operations, requiring only one operation to assemble and pack the inner member B, one operation to form the tube A, and one operation to secure the accordion fold of the inner member B to the outer member A. 10 Where the inner member B is made in accordance with Figs. 11 and 12 the inner member may be wrapped and glued to the protective shell surrounding the tube or bulb on an automatic folding and gluing machine. 15

The container may be easily and quickly manipulated by the storekeeper to test the tube or bulb at any time. Slight pressure exerted upon the partition 14 immediately ejects the contact end *p* of the tube or bulb, making the same immediately accessible for insertion into a suitable test socket. It is impossible to eject the inner member B farther than that required to effect a proper test of the article T since the inner member B and the outer member A are 20 secured together by the rivet 50 and the accordion fold. The rivet or eyelet 50 is so designed that it is impossible to separate the accordion fold from the outer member A without leaving noticeable evidence of tampering or ac- 30 tual irreparable destruction of the container. Thus it is impossible to remove the article originally packed in the container and replace the same with another article without giving the purchaser ample notice that the container has 35 been tampered with.

The container herein presented is especially designed for the merchandising of radio tubes, electric light bulbs, gas mantles and other objects which are generally tested to determine 40 their condition prior to sale. The bootlegging of inferior products and the unauthorized packing of such products in containers originally used or designed for the packaging of another product is thus thwarted and prevented. 45

While certain novel features of the invention have been disclosed and are pointed out in the annexed claims, it will be understood that various omissions, substitutions and changes may be made by those skilled in the art without de- 50 parting from the spirit of the invention.

What is claimed is:

1. A container for radio tubes and the like including, an outer member, a partition telescoping within the outer member supporting one 55 end of the tube, means for closing the other end of the member, and means for limiting the telescoping movement of said partition.

2. A container for radio tubes and the like including, an outer tubular member, a partition telescoping within the outer member extending 60 transversely across the same and providing a support for one end of the tube, a second transverse partition telescoping within the outer member confining the tube therein, and means 65 for limiting the telescoping movement of said partitions.

3. A container for radio tubes and the like including, an outer tubular member, a transverse partition telescoping within said member 70 providing a support for the tube, means for permanently closing the other end of the member, and means for limiting the telescoping movement of said partition, said means includ- 75 ing an element permanently connecting said

- partition and outer member which cannot be removed or detached to effectuate removal of the tube without leaving visible evidence of tampering.

5. 4. A container for radio tubes and the like including, an outer member of tubular form, a transverse partition telescoped within said member closing one end thereof, means for closing the other end of the member, and means limiting the telescoping movement of said partition comprising an accordion fold associated with said partition, and an element permanently connecting said fold to the outer member which cannot be removed or detached to effectuate removal of the contents without leaving visible evidence of tampering.

10. 5. A container for radio tubes and the like including, a tubular outer member, transverse partitions telescoping within the outer member closing the ends thereof, an element connecting said partitions, and means for limiting the telescoping movement of said partitions, said means being permanently connected to one of said partitions and the outer member which cannot be removed or detached to remove the contents without leaving visible evidence of tampering.

15. 6. A container for radio tubes and the like including, a tubular outer member, a transverse partition telescoping within the outer member closing one end thereof, means for closing the other end of the member and confining the tube therein, an opening in said partition through which the test end of said tube extends, and means limiting the telescoping movement of said portion comprising an accordion fold associated with said partition, and a securing element permanently connecting to said accordion fold and the outer member which cannot be removed or detached to effectuate removal of the contents without leaving visible evidence of tampering.

20. 7. A container for radio tubes and the like including, a tubular outer member, transverse partitions telescoping within the outer member closing the ends thereof and confining the tube therebetween, a side wall portion connecting said partitions, an opening in one of said partitions through which the test end of said tube extends, and means limiting the telescoping movement of said partitions, said means permanently connecting one of said partitions to the outer member which cannot be removed or detached to effectuate removal of the contents without leaving visible evidence of tampering.

25. 8. A container for radio tubes and the like including, a tubular outer member, transverse partitions telescoping within the outer member closing the ends thereof and confining the tube therebetween, a side wall portion connecting said partitions, an opening in one of said partitions through which the test end of said tube extends, and means including an accordion fold associated with one of said partitions, and a metallic element permanently connecting the accordion fold to the outer member which cannot be removed or detached to effectuate removal of the contents without leaving visible evidence of tampering.

30. 9. A container for radio tubes and the like including, a tubular outer member, transverse partitions telescoping within the outer member closing the ends thereof and confining the tube therebetween, side wall portions connecting said partitions, an opening in one of said

35. 10. A container for radio tubes and the like including, a tubular outer member, transverse partitions telescoping within said member closing the ends thereof and confining the tube therein, an element connecting said partitions, guide flaps extending from said partitions, and means limiting the telescoping movement of said partitions, said means permanently connecting the outer member to one of said partitions which cannot be removed or detached to effectuate removal of the contents without leaving visible evidence of tampering.

40. 11. A container for radio tubes and the like including, a tubular outer member, transverse partitions telescoping within the outer container closing the ends thereof and confining the tube therein, an opening in one of said partitions through which the test end of said tube extends, an opening in the other partition operative to center the tube therein, and means limiting the telescoping movement of said partitions, said means permanently connecting said partitions to the outer member which cannot be removed or detached to effectuate removal of the contents without leaving visible evidence of tampering.

45. 12. A container for articles to be tested prior to sale including a tubular outer member, transverse partitions telescoping within the outer member closing the ends thereof and confining the tube therein, an opening in one of said partitions through which the test end of said tube extends, an opening in the other partition operative to center the tube therein, side wall portions connecting said partitions, and means limiting the telescoping movement of said partitions, said means comprising accordion folds associated with one of said partitions, and elements permanently connecting said accordion folds to the outer member which cannot be removed or detached to effectuate removal of the contents without leaving visible evidence of tampering.

50. 13. A package for radio tubes and the like including, a tubular outer member, a transverse partition telescoped within said member closing one end thereof, means closing the other end of said member, a corrugated protecting shell surrounding the tube confined between said telescoping partition and end closing means, and means limiting the telescoping movement of said partition, said means permanently connecting said partition to the outer member which cannot be removed or detached to effectuate removal of the tube without leaving visible evidence of tampering.

55. 14. A package for radio tubes and the like including, a tubular outer member, partitions telescoping within the outer member closing the ends thereof and confining the tube therebetween, a protective shell surrounding said tube, side wall flaps extending from said partitions and fixed to said shell, and means limiting the telescoping movement of said partitions, said means permanently connecting said partitions to the outer member which cannot be removed or detached to effectuate removal of the contents without leaving visible evidence of tampering.

60. 15. A package for radio tubes and the like including, a tubular outer member, partitions telescoping within the outer member closing the ends thereof and confining the tube therebetween, side wall flaps extending from said partitions and fixed to said shell, and means limiting the telescoping movement of said partitions, said means permanently connecting said partitions to the outer member which cannot be removed or detached to effectuate removal of the contents without leaving visible evidence of tampering.

65. 16. A package for radio tubes and the like including, a tubular outer member, partitions telescoping within the outer member closing the ends thereof and confining the tube therebetween, side wall flaps extending from said partitions and fixed to said shell, and means limiting the telescoping movement of said partitions, said means permanently connecting said partitions to the outer member which cannot be removed or detached to effectuate removal of the contents without leaving visible evidence of tampering.

70. 17. A package for radio tubes and the like including, a tubular outer member, partitions telescoping within the outer member closing the ends thereof and confining the tube therebetween, side wall flaps extending from said partitions and fixed to said shell, and means limiting the telescoping movement of said partitions, said means permanently connecting said partitions to the outer member which cannot be removed or detached to effectuate removal of the contents without leaving visible evidence of tampering.

75. 18. A package for radio tubes and the like including, a tubular outer member, partitions telescoping within the outer member closing the ends thereof and confining the tube therebetween, side wall flaps extending from said partitions and fixed to said shell, and means limiting the telescoping movement of said partitions, said means permanently connecting said partitions to the outer member which cannot be removed or detached to effectuate removal of the contents without leaving visible evidence of tampering.

15. A package for radio tubes and the like including, a tubular outer member, partitions telescoping within the outer member closing the ends thereof and confining the tube therebetween, a protective shell surrounding said tube, a side wall portion connecting said partitions fixed to said protective shell, and means limiting the telescoping movement of said partitions, said means permanently connecting said partitions to the outer member which cannot be removed or detached to effectuate removal of the contents without leaving visible evidence of tampering. 5
16. A package for radio tubes and the like including, a tubular outer member, partitions telescoping within the outer member closing the ends thereof and confining the tube therebetween, a protective shell surrounding said tube, a side wall portion connecting said partitions, flaps extending from said partitions glued to said protective shell, and means limiting the telescoping movement of said partitions, said means permanently connecting said partitions to the outer member which cannot be removed or detached to effectuate removal of the contents 10 without leaving visible evidence of tampering. 15
17. A package for radio tubes and the like including, a tubular outer member, partitions telescoping within the outer member closing the ends thereof and confining the tube therebetween, interlocking flaps connecting said transverse partitions, and means limiting the telescoping movement of said partitions, said means permanently connecting said partitions to the outer member which cannot be removed or detached 20 to effectuate removal of the contents without leaving visible evidence of tampering. 25
18. A packaging for radio tubes and the like including, a tubular outer member, partitions telescoping within the outer member closing the ends thereof and confining the tube therebetween, a side wall portion connecting said partitions on one side thereof, interlocking flaps connecting the partitions on the other side thereof, and means limiting the telescoping movement of said partitions, said means permanently connecting said partitions to the outer member which cannot be removed or detached 30 to effectuate removal of the contents without leaving visible evidence of tampering. 35
19. A package for radio tubes and the like which includes, a strip surrounding said tube having an opening therein through which the test end of the tube extends, an outer member telescoping over said strip and tube, and means permanently connecting said strip and outer member limiting the telescoping movement of said strip and tube within the outer member. 40
20. A package for radio tubes and the like which includes, a continuous strip of paperboard material longitudinally surrounding said tube, said strip having an opening therein through which the test end of the tube extends, an outer member telescoping over said strip and tube, and means including an accordion fold permanently connecting said strip to said outer member permanently limiting the telescoping movement of the test end of the tube. 45
21. A package for radio tubes and the like which includes, a corrugated protective shell surrounding said tube, a strip of paperboard material longitudinally surrounding said tube and shell, said strip having an opening therein 50 through which the test end of the tube extends, a tubular outer member telescoping over said strip and tube, and means permanently connecting said strip to said outer member permitting a limited telescoping movement of the test end of said tube. 55
22. A container for radio tubes and the like which includes, a tubular outer member, transverse partitions telescoping within the outer member closing the ends thereof, an element connecting said partitions, and means for limiting the telescoping movement of said partitions which cannot be removed or detached without leaving visible evidence of tampering. 60
23. A container for radio tubes and the like which includes, a tubular outer member, a transverse partition telescoping within the outer member closing one end thereof, means for closing the other end of the member and confining the tube therein, an opening in said partition through which the test end of said tube extends, and means limiting the telescoping movement of said partition which cannot be removed or detached to effectuate removal of the contents without leaving visible evidence of tampering. 65
24. A container for radio tubes and the like which includes, a tubular outer member, transverse partitions telescoping within the outer member closing the ends thereof and confining the tube therebetween, a side wall portion connecting said partitions, an opening in one of said partitions through which the test end of said tube extends, and means limiting the telescoping movement of said partitions which cannot be removed or detached to effectuate removal of the contents without leaving visible evidence of tampering. 70
25. A package for radio tubes and the like including, a tubular outer member, a strip longitudinally surrounding said tube telescoping within the outer member and closing the ends thereof, means connecting the ends of said strip, and means limiting the telescoping movement thereof, said means permanently connecting said strip to the outer member which cannot be removed or detached to effectuate removal of the contents without leaving visible signs of tampering. 75
26. A package for radio tubes and the like including, a tubular outer member, a paperboard strip longitudinally surrounding said tube and telescoping within said outer member, said strip having partition portions engaging the ends of said tube and extending transversely across said outer member, and means limiting the telescoping movement of said partition portions which cannot be removed or detached to effectuate removal of the contents without leaving visible evidence of tampering. 80
27. A package for radio tubes and the like including, a tubular outer member, a paperboard strip longitudinally surrounding said tube telescoping within said outer member, means connecting the ends of said strip so positioned as to be inaccessible from the open ends of said tube, and means limiting the telescoping movement of said strip, said means permanently connecting said partitions to the outer member which cannot be removed or detached to effectuate removal of the contents without leaving visible evidence of tampering. 85

WILLIAM A. RINGLER.
